UNITED STATES PATENT OFFICE.

FRANK A. WELLS, OF NEW YORK, N. Y.

DESIGN FOR A SITZ-BATH TUB.

SPECIFICATION forming part of Design No. 34,144, dated February 26, 1901.

Application filed January 30, 1901. Serial No. 45,391. Term of patent 7 years.

To all whom it may concern:

Be it known that I, FRANK A. WELLS, a citizen of the United States, residing in New York city, borough of Manhattan, State of New York, have invented and produced a new and original Design for Sitz-Bath Tubs, of which the following is a specification, reference being had to the accompanying drawings, forming part hereof, wherein—

10 Figure 1 is a front elevation of a sitz-bath tub embodying my design, and Fig. 2 is a vertical cross-section thereof.

The essential feature of my design consists in a sitz-bath tub having its body or bowl portion of curved contour in a vertical direction substantially in the form of a double ogee, and from the rear portion of the body an upwardly-extending back is provided with a rim or flange along the front edges of the arm portions, the outer surface of the extended back wall above the main body having a concave curve, the corresponding front wall thereof having a convex curve.

In the accompanying drawings the letter A indicates generally the sitz-bath tub, and the body portion A' thereof at its open top

has a flaring rim *a*, below which is a concave curve *b*, below which is a convex curve *c*, and below the latter the wall is curved inwardly at *d*, and a rounded or convexly-formed flange *e* extends along the bottom, said curves and rims producing on the exterior of the bowl portion a double-ogee form extending symmetrically along the sides. Above the body portion A' is a back *B*, the side walls or arms *B'* of which from about the mid-portion of the sides of the bowl curve upwardly and rearwardly at *f* to the top edge *g*, the front edges of the side walls *B'* being rounded at *f'*, and the back wall has an inward or concave curve at *i*, and below the same said curve merges into the convex curve *c* at the body portion, the front wall of the back opposite to the curve *i* being curved convexly at *j*.

What I claim is—

The design for a sitz-bath tub, substantially as shown and described.

FRANK A. WELLS.
